UNITED STATES PATENT OFFICE.

JOHN J. SIMMONDS, OF IOLA, KANSAS, ASSIGNOR TO THE SIMMONDS ENGINEERING COMPANY, OF IOLA, KANSAS, A CORPORATION OF KANSAS.

RETORT-DISCHARGING MACHINE.

1,110,081.

Specification of Letters Patent. Patented Sept. 8, 1914.

Application filed March 9, 1914. Serial No. 823,331.

To all whom it may concern:

Be it known that I, JOHN J. SIMMONDS, a citizen of the United States, residing at Iola, county of Allen, State of Kansas, have 5 invented certain new and useful improvements in Retort-Discharging Machines; and I do hereby declare the following to be a full, clear, and exact description of the invention, such as will enable others skilled 10 in the art to which it appertains to make and use the same.

The present invention comprises an apparatus or machine for removing from furnace retorts the residue remaining after heat 15 treatment of ore therein.

In accordance with the present invention the machine comprises mechanically driven elements arranged to enter the retorts of a furnace, and to clean them out, those elements, in the preferred embodiment here disclosed in detail, comprising endless chains movable over suitable sprocket wheels or idlers, and carrying scrapers which progressively remove the residue from the retorts 25 simultaneously with the advance of the cleaning elements thereinto.

It is an object of the present invention to provide a machine capable of discharging a plurality of retorts simultaneously, this machine preferably being movable along the trackway from one group of retorts to another, so that the discharging operation may be carried on progressively throughout the length of the furnace. As a means for producing simultaneous and progressive advance of the cleaning elements or plungers into their respective retorts, each of these cleaning elements is supported on a carriage mounted in suitable guideways, and a main 35 or master carriage is utilized to shift all of the plungers simultaneously either forward or backward.

It is a further object of the present invention to maintain effective driving connection 45 between the plungers or scrapers and a suitably mounted motor, irrespective of the advancement or retraction of the scrapers, this being preferably effected by means of a main driving chain mounted on the movable carriage and having projecting lugs which operatively engage with corresponding lugs on the scraping chains. Suitable power driven mechanism is provided for shifting the main carriage across its supporting frame when

the plungers are to be advanced into their 55 retorts or withdrawn therefrom, and hand controlled mechanism is provided for reversing the direction of movement of the carriage on its frame, and automatic controlling means may also be provided for interrupting forward or backward movement of the carriage at a predetermined point when desired.

Other objects and advantages of the present invention will be made clear by the following detailed description, which is to be taken in conjunction with the accompanying drawings, wherein—

Figure 1 is a side elevation of the complete machine, showing the scrapers in working position in the retorts; Fig. 2 is a section on line 2—2 of Fig. 1; Fig. 3 is a diagrammatic side elevation illustrating the driving mechanism; Fig. 4 is a plan view of the machine, the plungers being broken 70 away; Fig. 5 is an enlarged detail of the clutch and reverse mechanism, whereby the forward and backward movements of the plungers are controlled; Fig. 6 is a detail showing a plunger in working position and 75 illustrating the driving mechanism for the scrapers of that plunger; Fig. 7 is an enlarged detail of the shifter mechanism for reversing the direction of movement of the plungers and is a section on line 7—7 of 80 Fig. 8; Fig. 8 illustrates the clutch shifting mechanism; Fig. 9 is a section on line 9—9 of Fig. 6, showing the chutes for deflecting 85 the scraped out material sidewise so that it does not fall on the mechanism immediately 90 below; Fig. 10 is a plan view of a plunger and its carriage; Fig. 11 is a side view of the same with the scraper chain omitted.

The construction illustrated in the drawings comprises a truck 10 mounted on wheels 95 11 and movable along a trackway which is laid in front of a retort furnace to be discharged. Supported on this truck is a frame consisting of uprights 12 connected at the top by transverse channels 13, the flanges 100 of which form a guideway for the reception of rollers on a movable carriage. The movable carriage comprises a pair of channel members 14 arranged vertically in the frame and supported on a truck, consisting 105 of a horizontal plate 15 (Fig. 7), provided at its ends with rollers 16, which bear on the inturned flanges of the channel mem-

bers 13 at the top of the frame. This carriage is movable toward and from the furnace and constitutes the mechanism for forcing the plungers into their retorts and for 5 withdrawing them therefrom.

Mounted between the uprights 12 of the frame are a plurality of channel bars 17 grouped in pairs to form upwardly inclined guideways in each of which an auxiliary carriage is mounted to move toward and from the retorts. As shown in Fig. 11 each of these auxiliary carriages comprises a frame 18 with supporting rollers 19 and 20 at its front and rear ends, respectively, these 10 rollers being received in their respective channels 17, as shown in Fig. 3, so that the carriage is adapted to slide back and forth along the inclined guideway afforded for it by its channels 17. Each frame 18 also 15 carries rollers 21 and 22 bearing respectively on the front and rear edges of the channel members 14, which make up the driving carriage. It will be seen, therefore, that as the main carriage is moved toward or from the furnace, it will carry with it all of the 20 auxiliary carriages, and these auxiliary carriages will have at the same time an upward movement due to the upward inclination of the channel guides 17.

30 At the front end of each auxiliary carriage and pivotally mounted at 23, is a plunger comprising three tubes, 24, 25 and 26, grouped as shown in Fig. 10, and carrying at their forward end a yoke 27 serving 35 as a bearing member for a sprocket wheel 28 over which passes an endless chain 29 (Fig. 6), each link of which has a projecting finger 30 for use in driving the chain, and some of the links of which carry flights 40 or scrapers 31 which project from the chain to serve in scraping away the residue from the retort tube 32. The rear end of each plunger comprises a fitting 34 of yoke shape bearing a short shaft 35 (Fig. 11) whereon 45 is mounted a second sprocket wheel 36, over which said chain 29 passes. The extreme rear end of fitting 34 is provided with rearwardly extending lugs 37 equipped with adjusting screws 38, whereby the angular 50 relation of the plunger may be adjusted with respect to its carriage by rocking the plunger slightly about its pivotal center 23. When the plunger is in action it may float 55 upward about its pivotal center 23, but its downward movement is limited by the said screws 38.

Mounted on each auxiliary carriage in alignment with the sprocket wheel 36 of its plunger, is an idler 39 in the form of a 60 sprocket, and this engages with the main driving chain 40 (Fig. 3) which passes upward between each idler 39 and its sprocket 36, and which carries forwardly projecting lugs adapted to engage with the lugs 30 of 65 the scraper chains and thereby actuate those

chains. Driving chain 40 serves to drive all of the scraper chains and the idlers 39 hold chain 40 to its work.

The power for driving the scraper chains of the plungers, as well as for advancing the 70 plungers into their respective retorts, and withdrawing them therefrom, is derived from an electric motor 41, or other suitable engine, carried on the truck. This motor may also be utilized for moving the truck 75 along the railway, and for that purpose there is provided on one of the truck axles a worm gear 42 which meshes with a worm 43 carried on a vertical shaft 44, the upper end of which is provided with a hand wheel 45. Splined on shaft 44 are a pair of friction disks 46 and 47, either of which may be brought into contact with a friction disk 48 on the motor shaft by means of a hand lever 500 (Fig. 1) acting through a yoke, 80 the ends of which are provided with collars 510 each having an inclined face for engagement with the cooperating faces of brackets bolted to the motor frame. Shifting hand lever 500 in one direction forces disk 46 into 85 driving engagement with armature disk 48 and allows the motor to drive the truck 10 along the railway, and swinging the hand lever in the other direction reverses the direction of movement of the truck. Small 90 adjustments in the position of the truck may be made directly by hand through the hand wheel 45.

Motor 40 is connected through belt 49 with the main driving pulley 50 of the machine, and that pulley is mounted on a shaft 53 in bearings carried by the top of the main carriage and so moves forward or backward in accordance with the movements of the plungers. To compensate for the variation 105 in distance between the pulley and the motor there is provided a belt tightener consisting of an idler pulley 51 carried on an arm 52 which swings about the shaft 53 whereon the pulley is mounted, and which 110 is rigidly connected with another arm 54 carrying a weight 55. The weight tends to swing idler 51 in the direction to tighten the belt, and this tightening may be augmented by hand by manipulation of the 115 hand lever 56, which constitutes a rigid extension of arm 52. Rigidly mounted on shaft 53 is the main driving sprocket 57, whereby the main driving chain 40 is actuated, but, as shown in Fig. 3, this chain 40, 120 before passing into driving engagement with the scraper chains of the plungers, goes over a second sprocket wheel 58.

Referring to Fig. 5 it will be seen that the second sprocket wheel 58 is keyed to a hollow shaft 59 and carries on its hub a small sprocket 60. Hollow shaft 59 is carried in bearings 61, 62, supported on the vertical channels 14 which make up the main carriage, and so is movable with the main driv- 130

ing sprocket 57 and its belt wheel 50 when the carriage moves toward or from the retorts.

Within hollow shaft 59 and turning freely therein is a solid shaft 63, one end of which carries a sprocket wheel 64 keyed rigidly thereto, and the other end of which carries a sliding collar 65 bearing projecting pins 66 which pass through the hub of a sprocket wheel 67 keyed to shaft 63, these pins being adapted to seat into recesses in the enlarged end 68 of hollow tube 59 where it overlies the end of bearing 61. By the outward movement of collar 65 the pins 66 can be withdrawn and hollow tube 59 can rotate while the solid shaft 63 and its sprockets 64 and 67 remain stationary, but on inward movement of collar 65, the pins 66 seat in their sockets and the solid shaft is locked to the hollow shaft, and sprockets 58, 60, 64 and 67 all turn together.

Mounted on channels 14 is a third shaft 69 bearing at one end a sprocket 70 in alignment with sprocket 64, and at the other end a sprocket 71 in alignment with sprocket 67. Sprockets 70 and 71 are keyed to shaft 69, but that shaft also carries a third sprocket 72, loosely mounted and provided with a notched hub 73, serviceable as a clutch member. Splined on shaft 69 and turning therewith, but free to move longitudinally thereon is a clutch collar 74 whereby sprocket 72 may be effectively connected with shaft 69. Sprocket 72 is connected by a chain with sprocket 60 and so rotates continuously whenever the latter is running, but it can be effectively connected or disconnected with shaft 69 to drive sprockets 70 and 71, as occasion may require.

The mechanism used for shifting the carriage across the frame of the machine when the plungers are to be introduced or withdrawn, comprises a pair of chains 75 (Fig. 3), one on each side of the frame, and each having its ends connected at 76 to the lower end of a channel 14. Each chain 75 passes over idlers 77 at the lower corners of the frame, and other idlers 78 on the upper corners, and passes as shown in Fig. 3 over the sprocket wheels 64 and 70 (the arrangement being the same on the other side of the frame). Sprocket 64 can be used to shift the carriage backward and withdraw the plungers, and sprocket 70 can be used to advance the carriage and push the plungers into the retorts, and this advancement or retraction goes on while the scraper chains of the plungers are in motion.

As a means for manually controlling the forward or backward movement of the carriage, there is provided a hand lever 79 (Figs. 1 and 8), pivoted to the top of the carriage at 80, and connected near its middle with a push bar 81. (Figs. 5 and 8.) This push bar carries at one end a yoke 82 for

shifting the sliding collar 65 on shaft 63, but it also carries a second yoke 83 co-operating with the clutch member 74, so that when collar 65 is moved outward to effectively disconnect hollow shaft 59 from solid shaft 63, the clutch members 74 and 73 may be thrown into driving engagement. In mid-position both clutches are out.

With the push bar 81 and the clutch mechanism in the position shown in Fig. 5, sprockets 64 and 67 will be positively driven from sprocket 58 by main chain 40, and will act through the drag chains 75 to move the carriage away from the retorts, but when the push bar 81 is forced in, the sprockets 64 and 68 will become idlers, and sprockets 70 and 71, acting through chain 75, will move the carriage the other way. In addition to this hand control of the forward and backward movements of the main carriage, there is provided an automatic control shown more particularly in Figs. 5, 7 and 8. This automatic control consists of a short vertical shaft 84 supported in bearings on the inner face of one of the channels 14, and carrying at its lower end an arm 85, the outer slotted end of which engages with the pin 86 carried on the push bar 81. The upper end of shaft 84 carries a tripping arm 87 which passes outward through a slot in channel 14 into position for engagement with a stop 88 bolted to the horizontal top member 13 of the frame and adjustable thereon in accordance with the depth of the retorts to be cleaned. On forward movement of the carriage, the tripping arm 87 is ultimately brought into engagement with stop 88, and thereupon rocks shaft 84 so that by the action on pin 86 the push bar 81 is shifted into the neutral position, and the forward advance of the carriage is stopped. To limit in similar manner the extreme outward movement of the carriage, there is provided an adjustable stop 89 (Fig. 1), corresponding with the stop 88 of Fig. 5.

To prevent the material scraped from the retorts from falling on the scraping mechanism of retorts lower down, there is provided for each plunger a metal chute 90 (Fig. 9) supported at its edges on rods 91 and 92, and comprising a trough-shaped portion 93 fitting over the shelf casting of the furnace and against the ends of the retorts 32, said chute also comprising a laterally extending portion as shown in Fig. 9, whereby material coming from the retort will be deflected sidewise. The rods 91 and 92, which carry the chute, pass backward through lugs 94, and are each encircled by a coiled spring 95, and on forward movement of the plungers these springs force rods 91 and 92 outward until their chute abuts against the retort 2 with yielding pressure, on withdrawal of the plungers, the lugs on frame 18 engage with the hooks on the ends 130

of rods 91 and 92 and withdraw the chutes to clear the frame.

The operation of the device is as follows: With the motor running, the truck 10 is shifted along its track into alignment with the particular group of retorts to be emptied or scraped out, this movement being effected by operatively connecting the motor through its friction disk 48 to drive worm 43 in one direction or the other. When the plungers are in alignment with their respective retorts, the hand lever 79 is pushed in and the clutch members 73 and 74 are thereby thrown together and the outward movement of collar 65 withdraws pin 66 and operatively disconnects sprockets 64 and 67. Then by swinging the belt tightener, a driving connection may be established between the motor and belt wheel 50, and this drives shaft 53 and sprocket 57 mounted thereon, and the latter by acting on the main driving chain 40 starts all of the scraping chains into motion and also rotates sprocket wheel 58 and its associated sprocket 60, but the latter is permanently connected by a chain to sprocket 72, and with the clutch member 74 in engagement with member 73 this sprocket 72 will drive the shaft 69 and its rigidly connected sprockets 70 and 71. These, by acting on chains 75, as shown in Fig. 3, will move the main carriage toward the retorts, and by so doing will force each auxiliary carriage and its supported piston outward and upward into the retort, where the continuously moving chain with its scrapers can tear away the residue to be removed. On completion of the forward movement of the plungers, the arm 87 of the automatic control mechanism strikes stop 88 and slides clutch member 47 out of working position, so that the further forward movement of the carriages is prevented. Thereafter, the hand lever 79 may be pulled outward to establish driving connection to the sprockets 64 and 67, and these by action on chain 75 will withdraw the plungers until the automatic stop arm strikes its stop 89, (Fig. 1), and again interrupts the driving connection of the carriage. Simultaneously, with the advance of the plungers into their retorts, the spring-pressed chutes 90 come up against the open mouths of the retorts, and on withdrawal of the plungers, these chutes are withdrawn far enough to clear the furnace shelf and leave the machine free to move along to the next group of retorts.

I claim:

1. A furnace discharging machine, comprising a truck movable along a trackway, a frame carried by said truck, a carriage movable across said frame, and a plurality of plungers adapted for entry into retort tubes of a furnace, said plungers being advanced or retracted by movement of said carriage, each of said plungers carrying an

endless chain forming a scraper, and means on said truck for driving said scraper chains while in their respective retorts.

2. A furnace discharging machine, comprising a frame, a carriage movable horizontally across said frame, plungers actuated by said carriage and movable outward and upward to enter inclined retorts of a furnace and power driven chains on said plungers for cleaning the retorts simultaneously with the advance of the plungers thereto.

3. A machine for cleaning the residue from spelter furnace retorts, comprising a plunger movable progressively into a retort, an endless chain carried by said plunger and provided with scrapers and power driven means for actuating said chain simultaneously with advancement of said plunger into its retort.

4. In a machine for discharging spelter furnace retorts, a plunger, mechanical means for progressively advancing said plunger into its retort, scraping means carried by said plunger and including an endless chain and a power driven chain for actuating said scraper chain to clean the retort simultaneously with the advancement of the plunger thereto.

5. In a machine for discharging furnace retorts, the combination of a plurality of plungers arranged one above another, an endless conveyor carried by each plunger and provided with scrapers, means for advancing said plungers simultaneously into their respective retorts, and a common driving means for said chains operable simultaneously with the forward advance of the plungers.

6. In a furnace discharging machine, the combination of a plurality of plungers arranged one above another, scraping means carried by each plunger for emptying its retort, separate guideways for said plungers power driven means for advancing said plungers simultaneously, and a common driving means for the scrapers of said plungers operable simultaneously with the advance movement of the plungers into their respective retorts.

7. In a machine for discharging furnace retorts, the combination of a plurality of plungers arranged one above another, each of said plungers carrying an endless chain with scrapers, carriage mechanism supporting said plungers, power driven means for advancing said plungers into their respective tubes simultaneously, and a driving chain co-operating with the chains of said plungers to scrape the retorts simultaneously with the advancement of the plungers thereto.

8. In a retort discharging machine, the combination of a truck, a motor mounted thereon, a frame supported upon said truck, a carriage movable across said frame, a

- drive-shaft carried by said carriage, a belted connection between said drive-shaft and said motor, said connection remaining effective irrespective of movements of said carriage, and retort cleaning means connected to be driven by said drive shaft and movable into furnace retorts by forward movement of said carriage, and power driven means for advancing or retracting said carriage.
9. In a furnace discharging machine, the combination of a frame, a carriage movable across said frame, auxiliary carriages slidably mounted on said frame and controlled in position by said carriage, a plunger connected with each auxiliary carriage, an endless scraper chain for each plunger, a common driving chain for all of said scraper chains, a drive-shaft on said carriage for actuating said driving chain, and power driven means for moving said carriage backward or forward across said frame.
10. A furnace discharging machine, comprising a truck movable along a trackway in front of furnace retorts, a frame on said truck, a carriage movable across said frame, auxiliary carriages supported by said frame and movable with said frame, and a plunger for each auxiliary carriage, said plunger being adapted to enter a furnace retort and carrying an endless scraper, and driving mechanism for the scrapers of said plunger.
11. In a discharging machine for retort furnaces, the combination of a frame, a carriage mounted to move across said frame, a drag chain secured to the lower end of said carriage and passing over idlers at the corners of said frame, and power driven means on said carriage and acting on said chain to move the carriage either forward or backward across said frame, and retort scraping chains mounted for advancement or retraction with said carriage.
12. In a machine for discharging furnace retorts, the combination of a truck, a frame mounted thereon, a carriage movable across said frame, power driven means for shifting said carriage on said frame, a plurality of guideways on said frame, auxiliary carriages movable in unison along said guideways and across said frame, plungers adapted for entry into the retorts to be cleaned, said plungers bearing endless chains with scraping elements, and power driven means movable with said carriage and effective for driving the scraping elements of said plungers.
13. In a furnace discharging machine, the combination of a plurality of plungers arranged one above another and each including an endless chain with scrapers, of a common driving chain for said plunger chains, idlers for holding said driving chain in operative engagement with the plunger chains, and means for moving all of said plungers and said common driving chain toward or from the retorts to be cleaned while the driving connection is maintained.
14. In a machine for cleaning furnace retorts, the combination of a frame movable along a trackway, a carriage mounted to move horizontally across said frame, upwardly inclined guideways on said frame, retort cleaning chains adapted to advance along said guideway and into the retorts on forward movement of said carriage, power driven mechanism movable with said carriage for actuating the retort cleaning chains during their advance movement into the retorts, power driven mechanism for shifting said carriage across its frame and reversing mechanism for changing the direction of movement of said carriage on said frame when desired.
15. In a furnace cleaning machine, the combination of a frame, a carriage movable across said frame, a pair of drag chains connecting said carriage with said frame and driven by mechanism on the carriage, and automatic reversing means on said carriage for changing the direction of movement along said frame, and retort cleaning devices movable into and out of furnace retorts in accordance with the forward or backward movement of said carriage.
16. In a furnace discharging machine, the combination of a truck, a motor mounted thereon, a frame carried by said truck, a carriage mounted to move across said frame, a power shaft on said carriage, belted connection between said shaft and said motor, a belt tightener to adjust the tension of said belt in accordance with the position of the carriage on the frame, a plurality of upwardly inclined guideways on said frame, an auxiliary carriage in each of said guideways, a plunger pivotally mounted to the front of each auxiliary carriage, each plunger including an endless chain with scrapers adapted to enter and clean a furnace retort, a driving chain on said carriage and engaging the scraper chains of the plungers to drive the same, idlers for holding said driving chain to its work on the scraper chains, a drag chain connection between said frame and its carriage, actuating means on the carriage co-operating with said drag chain to shift the carriage on the frame, and reversing means for changing the direction of movement of said carriage on its frame.
- In testimony whereof I affix my signature, in presence of two witnesses.
